UNITED STATES PATENT OFFICE.

WILLIAM F. ELGIN, OF GLEN OLDEN, PENNSYLVANIA, ASSIGNOR TO H. K. MULFORD COMPANY, OF PHILADELPHIA, PENNSYLVANIA, A CORPORATION OF PENNSYLVANIA.

VACCIN-POINT.

1,233,998.

Specification of Letters Patent.

Patented July 17, 1917.

Application filed February 14, 1917. Serial No. 148,514.

To all whom it may concern:

Be it known that I, WILLIAM F. ELGIN, a citizen of the United States, and a resident of Glen Olden, Delaware county, State of Pennsylvania, have invented a Vaccin-Point, of which the following is a specification.

One object of this invention is to provide a so-called "point" of improved construction which, in addition to being available for use 10 as a scarifier, shall contain a definite quantity of vaccin or serum;—the invention more particularly contemplating a novel form of scarifier which shall be at all times ready for use as well as simple and inexpensive in 15 construction.

It is further desired to provide a vaccin point with a novel form of package whereby it is at all times maintained in an antiseptic condition and effectually prevented from 20 such movement as would be likely to cause its breakage during transportation.

Another object of the invention is to provide novel means for preventing movement of one or a number of vaccin points within 25 a container during transportation, the invention including also means for keeping said points in an antiseptic condition ready for immediate use.

These objects and other advantageous ends 30 I secure as hereinafter set forth, reference being had to the accompanying drawings, in which,

Figure 1 is a vertical section illustrating a package constructed according to my invention, and designed to hold and transport 35 a number of vaccin points;

Fig. 2 is a simplified form of the invention designed to include but a single vaccin point; and

Fig. 3 is a vertical section on an enlarged scale illustrating the vaccin point of my invention.

In the above drawings, 1 represents a length of glass tubing having a body portion 2 and a drawn out thinner part 3 which in the finished article is sealed. The opposite end of said tube is likewise sealed or hermetically closed off and has mounted in it a sharp metal, usually steel, scarifying pin 4, the lower end of the body 2 being preferably provided with a transverse notch 5 for the purpose of insuring breakage of the tube at a definite point adjacent its lower end when a suitable breaking stress is applied to it.

The hollow bore 6 of the tube contains a greater or less amount of vaccin, serum or the like which may be introduced by any suitable means, and is preferably provided with a discharging bulb 7 of rubber having 60 a neck portion 8 and a centrally placed annular rib 9;—there being openings in its opposite ends, of which that through said neck is designed to receive and closely fit over the reduced end 3 of the tube. The 65 neck 8 is also designed to tightly fit into a narrow elongated container in the form of a closed end glass tube or bottle 10, which under conditions of use, contains a small quantity of an antiseptic substance which may 70 be in liquid, solid or gaseous form. Formalin for example, may be used as such a substance.

Where it is desired that the container shall hold more than one point, I provide a relatively larger bottle or holder 10^a having a neck portion and preferably of the form shown in Fig. 1, and I place in the bottom of this a body of cotton 11, in which the antiseptic substance is contained. A number of vaccin points are then placed in the container with their scarifying pins 4 resting upon or extending into a body of cotton or other mass of more or less springy and usually absorbent material 11, the length of 80 said container and the amount of said cotton being such that these points, after their introduction, have little if any longitudinal movement. Another point 1^a, with its reduced end 3 inserted in the neck of the bulb 7, is finally placed in the container 10^a and the proportions of the various parts are such 85 that when the ellipsoidal or other suitably tapering portion 12 of the bulb, between its neck 8 and its central rib or flange 9, is forced into the neck 13 of the container, the consequent passage of its pin 4 into or its engagement with the material 11, causes the latter to expand or move upwardly into engagement with the pins 4 of the other points 90 so as to hold these from subsequent movement. Even though the container may thereafter be subjected to comparatively severe shocks, there is no rattling or such movement of the vaccin points as would 95 break or otherwise injure them.

Under conditions of use the bulb 7 with its attached tube 1 is removed from the container 10 or 10^a as the case may be, and the scarifying pin 4 is applied to the skin of a 110

patient so as to abrade or cut into the same to the desired extent. Thereafter the scarifier-carrying part or end of the glass tube is broken at the notch 5 by a bending force 5 exerted by the fingers of the operator, and the reduced end 3 is similarly broken inside the bulb 7;—i. e., without removing it from the bulb. A finger or thumb of the operator is then pressed over the hole 14 at 10 the upper end of the bulb and the latter is compressed, thus forcing out the small quantity of serum or vaccin within the tube and permitting it to be applied to or deposited on the previously scarified surface 15 of the patient's skin.

By the above arrangement of parts and method of procedure, the point is maintained in an antiseptic condition and is not exposed to the air or opened until after 20 the desired skin surface of the patient has been scarified by the aseptic pin 4 of the point. Thereafter the vaccin or serum is forced out of the tube without danger of contamination at either of its ends.

It is to be understood that by the term 25 "scarifying point" as used in the foregoing description and in the claims is meant any structure regardless of its form, which is suitable, or which is capable of being used 30 as a means, for abrading the skin for purposes of inoculation.

I claim;—

1. A vaccin or similar point consisting of a sealed glass tube containing liquid to

be administered; and a metal scarifying pin 35 rigidly sealed in one end of said tube.

2. A vaccin or similar point consisting of a sealed glass tube containing liquid to be administered and having one end portion 40 of reduced section to permit of its relatively easy breakage; with a metal scarifying point rigidly sealed in the opposite end of said tube.

3. The combination of a container formed with an open end; a bulb normally closing 45 said end; and a plurality of independent vaccin tubes in the container of which one extends into the bulb so as to be removable therewith; with a mass of relatively springy material engaging said points to prevent 50 their movement.

4. The combination of a container formed with an open end; a mass of relatively springy material in said container; a vaccin point in said container having one end immovably held by said springy material; and means at the opposite end of said container for immovably holding the second 55 end of the vaccin point.

5. The combination of a container formed 60 with an open end; a bulb normally closing said end; a mass of springy material in the container; and a vaccin point in the container having its ends respectively entering the springy material and the bulb so as to 65 be immovably held thereby.

In witness whereof I affix my signature:
WILLIAM F. ELGIN.
